GASEOUS FLOW REGULATOR

Sabinus H. Christensen, Boston, Mass., assignor
to Carrier Corporation, Syracuse, N. Y., a corporation of Delaware

Application April 15, 1948, Serial No. 21,249

2 Claims. (Cl. 230—114)

1

This invention relates to gaseous flow regulators and more particularly to an adjustable regulator for imparting or removing a spiral or twisting direction to gaseous flow through a circular duct.

Heretofore, in centrifugal compressors, for example, spin vanes have been provided to impart a desired rotation to gaseous refrigerant passing to an impeller. Generally, the angle at which such vanes were disposed was fixed but in some cases the vanes were adjustable in order to vary such angle. For most satisfactory results, it is essential that the leading edge of each vane be tangential to the direction of oncoming fluid flow. Thus, with a fixed vane only one direction of flow could exist during operation of the machine or inefficiencies would result. With adjustable vanes as heretofore known, any adjustment resulted in the leading edge being disposed at an angle to the direction of fluid flow which also resulted in inefficiency.

The chief object of the present invention is to provide a regulator in which the leading edges of the vanes are fixed and tangent to the direction of fluid flow while the body of the blade is flexible and may be deformed to impart or to remove a desired direction to the fluid flow.

An object of the present invention is to provide a regulator including flexible metal vanes having their leading edges fixed and tangent to the direction of oncoming fluid flow and means whereby the outer trailing edge of each vane may be twisted thus deforming the body of the vane to impart or to remove rotation or spin to the fluid flow. Other objects of my invention will be readily perceived from the following description.

This invention relates to a regulator for gaseous flow in a circular duct which comprises in combination a plurality of flexible, resilient vanes having their leading edges fixed and tangent to the direction of oncoming fluid flow, and means for adjusting the angles of the vanes while the leading edges thereof are held in fixed position and tangent to the direction of fluid flow.

The attached drawing illustrates a preferred embodiment of my invention, in which:

Figure 1 is a view in elevation illustrating the present invention;

Figure 2 is a sectional view taken on line II—II 50 of Figure 1;

Figure 3 is a diagrammatic view illustrating the present invention embodied in a centrifugal compressor; and

Figure 4 is a sectional view taken on the line 55

2

IV—IV of Figure 3, illustrating a vane in straight and flexed positions.

Referring to the drawing, there is shown in Figures 1 and 2 a circular duct 2 having disposed therein a regulator 3 to impart or to remove rotation or spin to gaseous fluid passing therethrough. The regulator 3 comprises a central member 4, preferably formed in two sections as shown in Figure 2 to aid in assembly. A plurality of spaced vanes 5 extend radially from member 4. It is essential in my invention that vanes 5 be formed of a flexible, resilient material such as a flexible metal sheet as hereinafter described.

An insert member 6 is disposed within the wall of duct 2, member 6 having an opening 7 to receive a guide ring 8. The leading edge 9 of each vane is securely bolted as shown at 10 and 11 to insert 6 and to member 4 to hold it in fixed position and tangent to the direction of fluid flow.

Rods 12 are secured to the outer trailing edge 13 of each vane 5. On one side, rod 12' is disposed in an opening 14 in guide ring 8. On the opposite side, rod 12 extends through an opening 15 in guide ring 8. A shaft 16 extends through the wall of duct 2 carrying a crank 17 engaging rod 12. Gear 18 is disposed on the end of shaft 16 without duct 2 and may be actuated automatically or manually to rotate shaft 16, thereby rotating crank 17 to rotate ring 8 and twisting the outer trailing edge 13 of vane 5 as shown in dotted outline in Figure 4 to deform the body of the vane to impart or to remove a desired spin to the fluid flow. It will be appreciated vanes 5 may be twisted to produce either a right-hand or a left-hand spiral flow with equal efficiency.

In Figure 3, I have illustrated diagrammatically the regulator employed in a centrifugal compressor as a pre-rotation guide vane disposed at the inlet 19 to a centrifugal impeller 20 to impart a desired spiral flow to gaseous refrigerant passing to impeller 20. The regulator comprises a plurality of spaced vanes 21 composed of flexible sheet metal, the leading edges 22 of vanes 21 being fixed in position tangent to the direction of flow and the outer trailing edges 23 being twisted in a direction normal to the vane surface to deform the body of the vane thereby changing the direction of gaseous flow.

While I have disclosed that the trailing edges of the vanes may be tapered, it will be appreciated under some circumstances the leading edges may be tapered or both edges may be curved or straight as required for most satisfactory results. It will be appreciated, if desired,

the leading edges of the vanes may also be adjusted if desired similarly to the trailing edges.

The present regulator may be employed to impart or remove spin to a gaseous medium passing through a circular duct. It may be employed at the inlet to a centrifugal impeller for the purpose of shifting the surge point, maximum capacity and head while the speed is held constant. If desired, it may be employed to match the first stage and subsequent stages of an axial flow compressor to obtain the correct inflow angle to the rotating cascades. Likewise, the present invention may be utilized to remove residual spin of gas in a duct, for example, from the last stage of an axial flow compressor or from wind tunnel fans.

The present invention provides fluid rotation vanes which include all the advantages of prior structures while eliminating their disadvantages. Tangential entry to the fluid is maintained at all times irrespective of the required turning angle which eliminates loss due to separation. The adjustable vanes provide a wide range of effective turning angles. The efficiency of the present regulator is as good at all turning angles as the efficiency of prior structures when operating at their design turning angle.

While I have described a preferred embodiment of my invention, it will be understood my invention is not limited thereto since it may be otherwise embodied within the scope of the following claims.

I claim:

1. In a centrifugal compressor, the combination of an impeller for compressing fluids, and adjustable means disposed at the inlet to said impeller for determining the direction of fluid supplied to the impeller, said means comprising a plurality of flexible metal vanes, a central member, said vanes being mounted on and extending

radially from said central member, the leading edge of each vane being attached to the central member and held in fixed position tangent to the direction of fluid flow, a wall member surrounding the vanes, the outer edges of each vane being attached to the wall member, a movable guide ring disposed in said wall member, members extending from the trailing edge of each vane into openings in the guide ring, means for moving the guide ring to twist the outer trailing edge of each vane thereby deforming the body of the vane to vary the direction of fluid passing to the impeller.

2. In a regulator for gaseous flow in a circular duct, the combination of a central member placed substantially centrally in the duct, a plurality of flexible metal vanes mounted on the central member and extending radially therefrom, the leading edge of each vane being attached to the central member and held in fixed position tangent to the direction of fluid flow, a wall member surrounding the vanes, the leading edge of each vane being attached to the wall member, a movable guide ring placed in the wall member and extending circumferentially about the vanes, members extending from the trailing edge of each vane into openings in the guide ring, and means for moving the guide ring to deform the body of each vane whereby the direction of fluid flow may be adjusted.

SABINUS H. CHRISTENSEN.
